ELECTRIC CONNECTER

Ernst A. Larsson, Mansfield, Ohio, assignor to
The Ohio Brass Company, Mansfield, Ohio, a
corporation of New Jersey

Application February 16, 1937, Serial No. 126,612

4 Claims. (Cl. 173—332)

My invention relates to couplers and particularly to electric couplers for connecting conductors of one car with the conductors of a coupled car.

5 The use of electric couplers on cars both independent of and in combination with mechanical couplers is old, but under both conditions there has been difficulty in maintaining a constant connection between the electric couplers at all 10 time, and one object of my invention is to provide a new and improved form of electric coupler over-coming this difficulty.

My invention resides in the new and novel construction, combination, and relation of the 15 various parts hereinafter described and shown in the accompanying drawing.

In the drawing:—

Fig. 1 shows a face view of an electric coupler having incorporated therein my invention and 20 attached to a mechanical car coupler.

Fig. 2 is a view in partial section on the line 2—2 of Fig. 1.

Fig. 3 is a fragmentary view in partial section of two electric couplers having incorporated 25 therein a portion of my invention, in coupled relation.

Fig. 4 is a transverse sectional view on the line 4—4 of Fig. 2.

Fig. 5 is a view of a single coupling unit of 30 a type in common use and previously referred to herein.

In rounding curves there is a decided side or lateral strain to the two coupling units holding the cars mechanically in coupled relation. Where 35 the electric coupler is attached to the mechanical coupler this side strain is also transmitted to the electric coupler.

The effect of this side strain tends to separate the electric contacts of the electric coupler on 40 the far side of the coupler from the center of curvature of the track.

Under normal operations this slight relative movement of the electric couplers on one side will 45 not open the circuit from car to car with the common type of coupler (see Fig. 5), but it is found that particularly in the winter time when the cable leading to the coupler becomes loaded with ice due to condensation and freezing of leaking steam that the weight of such ice formation on the cable and the stiffness of the cable will not permit the contact member of the coupler to 50 operate freely under the action of the advancing spring, thus causing the circuit to open at the contacts under the conditions mentioned.

It will be noted in Fig. 5 that the conductor

is connected directly to the spring advanced contact member; thus, the contactor and the cable must move simultaneously.

To over-come the difficulty mentioned above, I have devised a construction in which the contact member at the front end of the coupler is free to reciprocate independent of the cable, thus when there is a tendency for the contactors to reciprocate for the reasons mentioned above, the advancing spring will maintain the contact members in coupled relation regardless of how much stress may be placed on the cable from the accumulation of ice or for other reasons.

In the preferred embodiment of my invention, I employ a support 1 which may be of various 15 forms and constructions and which I have shown as supported from a mechanical car coupler 2 by means of the bolts 3. In Fig. 1, I have shown the support as a casing 1 equipped with three electric connectors 4, but any number may be used to meet requirements. The car coupler 2 holds the cooperating electrical connectors on 20 two coupled cars in connected relation.

The casing 1 is provided with registering openings 5 and 6, the latter being shown as threaded. 25 Mounted in the opening 5 is an insulating bushing 7 having a cavity 8 in which is mounted a contactor 9 having a head 10 and stem 11.

The contactor reciprocates in the cavity 8 and is yieldingly held in its advanced position by 30 means of the spring 12. The contactor 9 is prevented from advancing beyond a predetermined amount by means of a nut or collar 13 pinned to the end of the stem 11 and abutting against the end face of the bushing 7. The bushing 7 is 35 provided with a flange 14 which butts against the inner adjacent face of the casing 1 preventing the bushing advancing.

Mounted upon the projecting end of the bushing 7 is a second insulating bushing 15 which projects rearwardly and through the opening 6 and is provided with shoulders 16 and 17. The bushing 15 is held in position by means of the metal bushing 18 which is adjustably held in position by threads cooperating with the threads of the 40 opening 6. The bushing 18 is provided with a flange 19 which butts against the adjacent outer face of the casing 1. The inner face of the bushing 18 engages the shoulder 16 on the insulating bushing 15, thus fixedly holding the bushing 15 45 in advanced position and in turn fixedly holding the bushing 7 in its advanced position.

Mounted within the bushing 15 at its rear end is a collar 20 having a projecting stem 21 which is semi-circular and cross-section. Secured to 50

the stem 21 by means of a bolt 22 is a cable connector 23. The cable connector has a flange 24 which holds the cable connector 23 and the parts 20 and 21 against longitudinal movement relative to the insulating bushing 15.

5 The conducting portion 25 of the cable 26 is secured in the socket portion of the connector 23 and in order to maintain the connection free from dirt, moisture, etc., a flexible rubber sleeve 10 27 is secured to the end of the bushing 15 by means of a clamp 28 and is secured to the outer surface of the cable insulation 29 by means of a clamp 30.

In order to electrically connect the cable 26 15 to the contact 9, I employ a plurality of very flexible conductors 31 having their ends secured to the members 13 and 20 as by means of welding or through the medium of a soldered connection. These flexible members 31 permit reciprocating 20 movement of the member 9 relative to the casing 1. The members 13 and 20 might be electrically connected by means of an interposed helical spring, but such a connection would be of very 25 low efficiency and would not conduct large currents which applicant's construction is intended for and which it will accomplish efficiently.

In order to maintain the abutting surfaces of the contactor heads 10 in as clean a condition as possible, I mount upon the projecting front end 30 of the bushing 1 a flexible rubber sleeve 32 held in place by the clamp 33. The bushing 32 abuts against the corresponding bushing on the counter-part coupler and the tendency is for these bushings to buckle more or less as shown in 35 Fig. 3, thus insuring a sealed joint.

By comparing the construction shown in Figs. 2 and 5, it will be apparent that the cable cannot influence in any manner the movement of the contactor 9. The members 31 are so flexible 40 that they readily yield under the reciprocal movement of the contactor 9.

Modifications will suggest themselves to those skilled in the art based upon my disclosure and, therefore, I wish to be limited only by my claims.

45 I claim:—

1. An electrical connecting device comprising a metallic support having a front and a rear wall and registering openings through the walls, an insulating bushing extending through one 50 opening, a second insulating bushing extending through the other opening and held in position by a bushing threadedly secured in the said other opening, the last said bushing holding the said second bushing against longitudinal movement 55 in one direction and the said second bushing holding the said first bushing against longitudinal movement in the same direction and the first bushing held against longitudinal movement in the other direction by the support, the first bush- 60 ing forming an apertured opening within the second bushing, a cable connector secured to the rear end of the said second insulating bushing against longitudinal movement in either direction, a reciprocating contactor mounted in the 65 first said bushing and projecting into the said second bushing, means on the reciprocating contactor and engaging the said shoulder of the first bushing to limit movement of the contactor in one direction, and a spring yieldingly 70 holding the contactor in its advance position, flexible means within the second bushing electrically connecting the cable connector and the con-

tactor, the first and second bushing insulating the conductors from the support and means to suspend the support from a car.

2. An electrical connecting device comprising a metallic support having a front wall and a rear wall and registering openings through the walls, insulating bushings extending through the openings, means to hold the bushings in fixed relation to the support, a terminal member at one end of one bushing and projecting within and 10 without the bushing and having means to receive a cable, an insulating bushing to protect the last said means, a reciprocating contactor mounted within one end of the other bushing and projecting from the bushing, the bushings insulating the terminal member and contactor from the support, means to yieldingly hold the contactor in its advanced position to engage a contactor on a counterpart device, flexible means positioned within the bushings to electrically connect the contactor and the terminal member. 15

3. An electrical connecting device comprising a metallic support member having a front and a rear wall with registering openings through the walls, an insulating bushing extending through the openings, a reciprocating contactor mounted in the said bushing at one end thereof and insulated from the support member by the bushing, the contactor projecting from the end of the bushing, means to yieldingly advance the contactor into engagement with a contactor on a cooperating connecting device and maintain said engagement, means to support the said support member and to cooperate with like means on a cooperating connecting device to yieldingly hold the connecting device in operative relation, means on the bushing to engage one wall and adjustable means cooperating with the other wall to engage the bushing to hold the bushing mounted in position in the wall openings, a connector mounted within the bushing adjacent the end remote from the contactor, a flexible member positioned within the bushing and connecting the contactor and connector, means on the connector to receive a cable and the end of the bushing extending beyond the connector to enclose the connection of the cable to the connector. 20

4. An electrical connecting device comprising a metallic support having a front wall and a rear wall and registering openings through the walls, an insulating bushing extending through the openings, means to hold the bushing in fixed relation to the support, a terminal member at one end of the bushing and projecting within and without the bushing and having means to receive a cable, a reciprocating contactor mounted within and projecting without the other end of the bushing, the bushing insulating the terminal member and the contactor from the metallic support, means to yieldingly hold the contactor in its advanced position to engage a contactor on a counterpart device, flexible means positioned within the bushing to electrically connect the contactor and the terminal member, and a flexible bushing surrounding the exposed end of the contactor but leaving the end face of the contactor exposed, the flexible bushing engaging a like bushing on a counterpart device to protect two contactors while in engagement.
